Thomas Lyons
Inventor.

United States Patent Office.

THOMAS LYONS, OF HARTFORD, ASSIGNOR TO RUSSELL & ERWIN MANUFACTURING COMPANY, OF NEW BRITAIN, CONNECTICUT.

Design No. 4,953, dated May 30, 1871.

DESIGN FOR AN OVEN-SHOVEL.

The Schedule referred to in these Letters Patent and making part of the same.

Be it known that I, THOMAS LYONS, of Hartford, in the county of Hartford and State of Connecticut, have invented and produced a new and original Design for an Oven-Shovel, of which the following, in connection with the photographic illustration, is a specification.

The purpose for which this oven-shovel is intended is for removing plates or other articles from heated ovens.

It may be used for various other purposes, as sifting ashes from coal.

The whole is cast or founded in one piece of metal.

Figure 1 shows the front or upper side of the oven-shovel, and

Figure 2 shows the reverse or lower side of the same.

The handle, when viewed from the upper side, fig. 1, at *a* shows convex form, and at *b* shows concave form, and the reverse when viewed from the lower side, as in fig. 2.

The braces *fff*, fig. 2, on the under side of the handle, are for the purpose of giving additional strength.

The body portion of the oven-shovel is made flat or nearly so, of thickness to give it sufficient strength.

Its circumference is scalloped *c c c*, except on the side opposite the handle at *e e*; but it may be of any regular or irregular shape.

Various-shaped openings or holes *d d d d* are made through the body of the shovel for the purpose of lightening it, and also to save material in its production.

The projection *ll* on the circumference opposite the handle is beveled on either side, to facilitate sliding the shovel under the article to be removed from the heated oven.

Claim.

What I claim as my invention, and desire to secure by Letters Patent, is—

The design for an oven-shovel, herein described and shown in the photographic illustration.

Witnesses: THOMAS LYONS.
